SURFACE TEST INDICATOR

Gerald C. Welch, Rochester, N. Y.

Application September 4, 1951, Serial No. 245,054

4 Claims. (Cl. 33—172)

1

This invention relates to surface test indicators, and more particularly to a casing construction therefor.

In an application Serial No. 119,626, filed October 5, 1949, there is disclosed a double face surface test indicator having enclosed dials and a wide indicator range. The present invention relates to improvements in the casing construction for such indicators, and the crystal mountings therefor. The improvements have to do with the provision of a more rugged casing, and a casing the main members of which are produced from a single die.

The above and other novel features of the invention will appear more fully hereinafter from the following detailed description when taken in conjunction with the accompanying drawings. It is expressly understood that the drawings are employed for purposes of illustration only and are not designed as a definition of the limits of the invention, reference being had for this purpose to the appended claims.

In the drawings, wherein like reference characters indicate like parts:

Figure 1 is a plan view of the surface test indicator;

Figure 2 is a plan of the surface test indicator with one side casing member removed;

Figure 3 is a longitudinal sectional view taken substantially on the line 3—3 of Figure 2;

Figure 4 is a view of the dial from the reverse side; and

Figure 5 is an exploded perspective view of the frame elements in assembly relation to one another.

Referring to the drawings, there is shown in Figures 1 to 3, a surface test indicator (twice normal size), the frame or casing of which comprises a top and bottom plate 10 and 12, respectively, and an intermediate plate 14, of the same or slightly greater thickness. The top and bottom plates 10 and 12 constitute cover plates, and together with the intermediate plate 14, which is cut out as at 16, provides a housing for the actuating and pointer mechanism.

Each of the top and bottom plates comprise a tapered arm portion 18, and an annular bezel frame or ring 20. The ring 20 is provided with an annular shouldered recess 22 for receiving the peripheral edge of the convex bezel 24.

The intermediate plate 14, by reason of the cut out portion 16, provides space for the actuating arm 26, pointer 28, and bias spring 29. The intermediate plate has an annular frame or ring portion, discontinuous by reason of the cut out portion 16, adapted to support a circular dial

2

disk 30. The ring is provided with a shouldered, annular recess 32, upon which the dial disk is seated, such recess having sufficient depth so that the dial, when seated, is centered with respect to the upper and lower surfaces 34 and 36 of the intermediate member. The diameter of the dial-receiving recess 32 is slightly less than the bezel-receiving recess 22, so that the intermediate plate acts in conjunction with the cover plates to form a deep annular groove for receiving the edges of the bezels. The dial is staked in place by points 38 sheared from the frame.

The cover and intermediate plates are secured together by screws 40, the heads of which are countersunk in the plate 10 and the shanks of which are threaded in the plate 12, such screws passing through corresponding apertures in the intermediate plate 14. The outer plates 10 and 12 are also secured together by screws 42 and 44, which form pivots for the actuating lever 26 and pointer 28, respectively.

As described in the copending application hereinabove referred to, the actuating lever 26 is frictionally held in the bifurcated end 46 of the ball arm member 48, which ball arm member is freely pivoted on the screw 42. The friction is developed by the resiliency of the folded-over portion 50 of the actuating arm or by a resilient dished spacer. The free end of the actuating arm is provided with spaced fingers 52 and 54 riding on pins 56 and 58 on the pointer. The hair spring 29 rides on the pin 56, and is secured at its other end in a slit in the bottom plate, as at 58, such slit being swaged closed after insertion of the spring.

The ball 60 is spherical, and of a diameter equal to or less than the root diameter of the threads 62, whereby a larger spherical ball member 64, having an internally threaded collar 66, may be positioned over the ball 60, the collar having a shoulder 68 adapted to abut a shoulder 70 at the base of the threads 62, whereby the ball 64 will be concentric with the ball 60 when screwed on the threads 62, with the shoulders 68 and 70 abutting.

The bottom plate may be provided with a mounting stud as shown in the above referred-to application, or if desired, the intermediate plate may be provided with an extension 72 in which a shouldered stud 74 is positioned. Such shouldered stud is provided with a thumb nut 76 for securing to a support arm 78. While a stud permanently fixed to the extension 72 is shown, it will be appreciated that the aperture 73 may be merely threaded, and the arm 78 secured

thereto by a thumb screw, or the aperture 17 in the arm threaded, and the thumb screw extended through the aperture 73.

The dial is lettered on opposite sides reversely, so that the indicator can be read from either side, and for this purpose, the pointer 28 is duplicated on opposite sides of the dial, as at 31 and 33, the pointer 31 being offset as at 35 to clear the dial. Both pointers are secured together by the collar 37 and the pins 56 and 58.

It will be seen that the indicator frame plates are of similar shape, and may be cut from heavy sheet stock by a single die, it being necessary, if the extension 72 on the intermediate plate is provided, to cut away such extension in preparing the cover plates 10 and 12, and to cut away the central portion 16 of the intermediate plate 14. The parts as thus cut may thereafter be finished by turning the respective shouldered recesses 22 and 32 in a lathe operation. The entire assembly, however, provides a practically indestructible casing, with deep bezel grooves whereby the indicator is protected from dirt and grime usually present in machine shops, where the indicator is generally used. The construction is such as to provide a wide angle scale for ease in reading indications thereon. While a convenient size has been indicated which would comprise the parts of the size as actually shown in Figure 5, and in which the plates are in the order of $\frac{1}{8}$ " stock, the outer plates being slightly less, such size is merely referred to as an example to indicate the compactness, ruggedness, and simplicity of the structure as a whole.

Although a single embodiment of the invention has been illustrated and described, it is to be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

1. In a surface test indicator, a housing comprising three flat plates having similar exterior contour, each comprising an arm portion, and an enlarged substantially annular indicator dial portion, means for securing said plates together, the outer plates comprising top and bottom covers and the intermediate plate being cut away to provide spaced side walls for said arm portions and a cavity for indicating and actuating mechanism, the annular portion of said outer plates having an inwardly directed annular shouldered recess for receiving a bezel, circular bezels having their peripheral edges mounted in said recesses, and the annular portion of the intermediate plate having an annular shouldered recess, the diameters of which are less than the diameters of said bezel recess, a circular dial seated in said intermediate plate recess, an indicator member having pointers extending in parallel spaced relation on opposite sides of said dial, and pivoted on the arm portions of said cover plates, and indicator actuating means projecting outwardly from the end of the arm, and pivoted on the arm portions of said cover plates adjacent the end thereof, said actuating means having a member adapted to engage said indicator for actuation thereof.

70

2. In a surface test indicator, a housing comprising three flat plates having similar exterior contour, each comprising an arm portion, and an enlarged substantially annular indicator dial portion, means for securing said plates together, the outer plates comprising top and bottom covers and the intermediate plate being cut away to provide spaced side walls for said arm portions and a cavity for indicating and actuating mechanism, the annular portions of each of said outer plates having an inwardly directed annular shouldered recess for receiving a bezel, circular bezels having their peripheral edges mounted in said recesses, and the annular portion of the intermediate plate having an annular shouldered recess, the diameters of which are less than the diameters of said bezel recess, a circular dial seated in said intermediate plate recess, an indicator member having pointers extending in parallel spaced relation on opposite sides of said dial, and pivoted on a screw extending through and normal to the arm portions of said cover plates, and indicator actuating means projecting outwardly from the end of the arm, and pivoted on a screw extending through and normal to the arm portions of said cover plates adjacent the end thereof, said actuating means having a member adapted to engage said indicator for actuation thereof.

3. In a surface test indicator, a housing comprising three flat plates having similar exterior contour, each comprising an arm portion, and an enlarged substantially annular indicator dial portion, means for securing said plates together, the outer plates comprising top and bottom covers and the intermediate plate being cut away to provide spaced side walls for said arm portions and a cavity for indicating and actuating mechanism, the annular portions of each of said outer plates having an inwardly directed annular shouldered recess for receiving a bezel, circular bezels having their peripheral edges mounted in said recesses, and the annular portion of the intermediate plate having an annular shouldered recess of a depth slightly greater than half the plate thickness, the inner and outer diameters of which shoulders are less than the diameters of said bezel recess, a circular dial seated in said intermediate plate recess and secured therein by pins sheared from the recess wall, an indicator member having pointers extending in parallel spaced relation on opposite sides of said dial, and pivoted on a screw extending through and normal to the arm portions of said cover plates, and indicator actuating means projecting outwardly from the end of the arm, and pivoted on a screw extending through and normal to the arm portions of said cover plates adjacent the end thereof, said actuating means having a member adapted to engage said indicator for actuation thereof, said means for securing said plates together comprising said screw pivots, and screws extending through the annular portions adjacent the peripheral edges thereof.

4. An indicator in accordance with claim 1, in which the intermediate plate is provided with an apertured extension portion extending beyond the marginal edges of the cover plates superimposed thereover.
